CLAIM

[**] Term: 7 Years

The ornamental design for a control panel for a fire control combat simulator, substantially as shown and described.

[21] Appl. No.: 786,733

DESCRIPTION

[22] Filed: Apr. 11, 1977

FIG. 1 is a perspective view illustrating in solid lines one embodiment of our control panel for a fire control combat simulator. The broken lines illustrate a cabinet containing said control panel, said cabinet being environmental structure shown for illustrative purposes only.
